(57) **CLAIM**

I claim the ornamental design for a golf putter head, as shown and described.

DESCRIPTION

FIG. 1 is a perspective view of a golf putter head showing my new design therefor;

FIG. 2 is a front elevational view thereof;

FIG. 3 is a side elevational view thereof showing a side facing the golfer when the golf putter head is in use;

FIG. 4 is a rear elevational view thereof;

FIG. 5 is a side elevational view thereof showing a side facing away from the golfer when the golf putter head is in use;

FIG. 6 is a top plan view thereof; and,

FIG. 7 is a bottom plan view thereof.

The broken line showing of a fragmented shaft is for illustrative purposes only and forms no part of the claimed design.
